UNITED STATES PATENT OFFICE.

ALEXANDER C. WOOD, OF NEW YORK, N. Y., ASSIGNOR TO ST. MUNGO MANUFACTURING COMPANY OF AMERICA, OF NEWARK, NEW JERSEY, A CORPORATION OF NEW JERSEY.

DESIGN FOR A GOLF-BALL.

44,227.

Specification for Design.

Patented June 17, 1913.

Application filed June 17, 1912. Serial No. 704,244. Term of patent 14 years.

To all whom it may concern:

Be it known that I, ALEXANDER C. WOOD, a subject of the King of Great Britain, residing at No. 548 Madison avenue, in the borough of Manhattan of the city of New York, in the State of New York, have invented a new, original, and ornamental Design for Golf-Balls, of which the following is a specification, reference being had to the accompanying drawing, forming a part thereof.

In the drawing, Figure 1 is a side or

equatorial view of my new design for golf ball. Fig. 2 is an end or polar view of the same.

On the actual ball, the crescents illustrated in the drawings are depressions.

I claim:

The ornamental design for a golf ball, as shown.

ALEXANDER C. WOOD.

In the presence of—

E. N. GEILFUSS,
G. MCGRANN.
